SHEET FEEDING DEVICE

Georg Spiess, Leipzig, Germany

Application May 29, 1931, Serial No. 540,968
In Germany February 19, 1930

12 Claims. (Cl. 271—38)

I have filed applications in Germany on Feb. 19, 1930, Aug. 28, 1930, Nov. 26, 1930, Dec. 1, 1930; Sweden May 6, 1931; Great Britain May 4, 1931.

The present invention relates to sheet feeding devices and more particularly to a sheet feeding device wherein the feed of a fanned out pile is automatically controlled from the pile itself by the employment of a ratchet and pawl gear operating upon the pile feeding means, which is controlled by a device operated by the pile in such manner that according to requirements it either performs useful work or runs idly. The known device comprising a coupling controlled by the sheet controlling device and arranged in 15 the linkage actuating the means for feeding the sheets forward or a ratchet and pawl gear directly connected with the aforesaid means the pawl of which is controlled by the device governing the feed of the sheet, has the disadvantage 20 that the linkage connected to the ratchet and pawl gear of the sheet feeding means prevents free access to the feed table and gives rise to considerable noise as a result of knocking, which may be very troublesome, particularly at high 25 rotational speeds.

The principal object of the present invention is to eliminate these disadvantages and with the object in view the ratchet and pawl gear is arranged on the frame of the sheet feeding device 30 separately from the sheet feeding means and is directly connected with the pile control device by which it is actuated and adjusted, the said ratchet and pawl gear driving the sheet feeding means by means of rotating driving members. 35 The sheet feeding means are arranged in such manner that they do not prevent free access to the pile table. The invention resides more particularly in the feature that by the action of a control member which is itself controlled by 40 the position of the front end of the pile, a further control member is actuated so as to prevent or permit the engagement with the ratchet, of the pawl of the ratchet and pawl gear connected with the rotating driving members of the sheet feeding 45 means.

According to the invention the control member consists of a segment which is provided with ratchet teeth, a recess serving for the reception of the operative members and a guide track upon 50 which the said operative members are adapted to run idly, and which segment, just according as the front edge of the pile does not or does influence a control device, either swings freely together with the pawl lever of the ratchet and pawl gear or is locked by means of a pawl 55 through the agency of a piston actuated by the sheet controlling means, for instance by means of a suction nozzle arranged on the pile table. In this way the result is attained that the forward feed of the pile is simplified and reliable 60

operation of the apparatus is ensured, whilst in addition to this the operation of the apparatus even when running at the highest speed is rendered entirely noiseless.

A preferred constructional form of the sheet feeding device according to the invention is illustrated by way of example in the accompanying drawings, as applied to a sheet feeding device for fanned out piles, wherein the separation of the sheets from the pile is effected by means of suction members. It will, of course, be understood that the invention may be similarly applied to a sheet feeding device operated by means of grippers or other devices.

Referring to the drawings:

Fig. 1 is a broken elevation of a sheet feeding device according to the invention, shown diagrammatically, all parts not necessary for the comprehension of the invention being omitted.

Fig. 2 is a plan drawn similarly to Fig. 1, and

Fig. 3 shows a part of Fig. 1 with the operative members of the ratchet and pawl gear in a different position.

In the drawings the reference numeral 1 denotes the frame of the sheet feeding device. In this frame the main shaft 2 (by which is meant the shaft which performs one revolution during one working operation) is journaled, and upon the shaft 2 a cam disc 3 is mounted by means of which a pawl carrying lever 5 which is loosely journaled on a shaft 6 is moved to and fro by means of a connecting rod 4. The lever 5 is provided at its end with a pawl 8 which is mounted on a pin 7 and also with a roller 10 adapted to rotate about a pin 9, and is urged by means of a spring 11 against the teeth of a ratchet 12, which is keyed on to a shaft 6 journaled in the frame 1. The rotational movements of the ratchet 12 caused by the action of the pawl 8 are transmitted through the agency of a bevel wheel 13 rigidly mounted on the shaft 6, through the bevel wheel 14, shaft 15, bevel wheels 16, 17 and pinions 18, 19, 20, 21, 22 to a pile conveying roller 23. The axle 24 upon which the pinion 19 is mounted is provided in known manner with rollers 25. By means of these rollers and co-operating rollers 26, bands 28 are led over a pile table 27, said rollers in conjunction with the pile conveying roller 23 and conveying bands 29 passing over rollers 25 effect the forward feed of the pile.

The forward feeding movement of the pile is limited by a suction nozzle 30 opening on to the surface of the feed table 27, which nozzle when it is overlapped by the front edge of the pile and is thereby closed causes a piston 32 to move in a casing 33 against the action of a spring 34, by means of the vacuum produced in a suction conduit 31 by means of an air pump (not shown in the drawings) connected thereto. An

100

105

110

115

120

- adjustable piston rod 35 connected to the piston 32 then presses upon the back of a pawl 36 and brings the latter into engagement with ratchet teeth provided on a segmental member 37 which 5 is loosely mounted on the shaft 6 adjacent to the ratchet wheel 12 between this latter and the side of the frame 1 of the sheet feeding device, and in consequence of the action of a spring 38 bears upon a projection 39 provided on an 10 extension of the pin 7 and swings together with the lever 5. On the one end of the segmental member 37 a member 40 carrying ratchet teeth is fixed by screws. At the other end the segmental member is provided with a recess 41 acting 15 as a stop for the pawl lever 8 in conjunction with the projection 39, and is further provided with a guide track 42 arranged concentrically with the shaft 6.
- On a shaft 43 journalled in the sides of the 20 frame 1 and serving by the aid of a handle (not shown on the drawings) for controlling the air admission device, a bell crank lever is mounted the one arm 44 of which is provided with a ball catch member (not shown on the drawings) 25 which drops into a recess 45 and maintains the ratchet and pawl devices in the positions determined by the stops 45 on which the arm 44 bears. In addition to the angle lever a catch member 47 is likewise provided at the end of 30 the shaft 43, which catch member is loosely mounted on the shaft, is secured by means of an adjusting ring and is provided with a pin 48 which bears on a stop provided on the second arm 44a of the angle lever, in consequence of the 35 action of a spring 49 connected to the catch member and the side of the frame respectively.
- In the case of the constructional example described the bell crank lever as shown in the figures is located in the position in which the 40 air control device is not affected and can thus operate freely under the action of its cam control members. If, however, the shaft 43 is turned in such manner that the bell crank lever 44 is secured in position by the upper stop 45, i. e. is 45 located in the position in which the air control device is out of action, then the catch member 47 follows the backwardly swinging arm 44a in as much as the pin 48 remains the contact with the stop of the arm 44a in consequence of 50 the action of the spring 49. On the catch member 47a recess 50 is provided which is adapted in the non-operative position of the air control device to enclose a pin 51 arranged laterally on the projection 39 of the segmental member 37 55 when the latter is swung back. If the shutting off of the air control device takes place, for example, at the moment when the projection 39 of the segmental member 37 rests on the pin 7 and is swung forward during the normal pile feeding operation together with the pawl lever 5, the pin 51 will be maintained in place by the recess 50 during the next return swinging movement. The sheet feeding device may also continue to run idly when the air control device 60 has been shut off or when it or the machine to which it is connected is adjusted.
- During the working stroke of the device the segmental member 37 swings over together with the pawl lever 5 under the action of the spring 38. The roller 10 rests in the recess 41 which is made of such a depth that the tooth of the pawl 8 can engage in the teeth of the ratchet 12 and can turn the latter forwards together with the pile conveying roller 23 through the agency 65 of the above described transmission gear. If,

however, the segmental member 37 is held in any given position as a consequence of the engagement of the pawl 36 with the ratchet teeth 40, the roller 10 rides out of the recess 41 on to the track 42, the radius of which is of such magnitude that the tooth of the pawl 8 cannot engage with the teeth of the ratchet 12, and the further operative movement of the pawl lever 5 at the conclusion of which the suction air acting on the nozzle 30 is shut off, no longer exerts any influence on the forward feeding movement of the pile. On the return of the pawl lever 5 the pin 7 carries the projection 39 and consequently also the segmental member 37 back into the initial position in which the suction air acting on the nozzle 30 is again put into operation, as a result of which the swinging movement of the segmental member is again rendered possible until the nozzle is once more covered by the succeeding sheet from the pile.

On the shaft 2 a cam disc 53 is mounted, which co-operates with a roller 54 provided on a lever 55, which is fulcrumed on a transverse rod 56 mounted on the frame. On another transverse rod 57, which carries the feed table 27, bearings 58 for pivot pins 59 on which arms 60 are mounted, are provided at the two sides of the table. The said arms 60 carry at their ends a raising batten 61 and form with this latter and a transverse rod 62 a rigid frame, which bears through the medium 105 of a laterally located roller 63 on a bearing surface provided on the lever 55. The raising batten will thus be raised and lowered during a working operation in correspondence with the movements of the lever 55 caused by the cam disc 53, the 110 raising movement taking place when a sheet is brought by the sheet lifting device 52 on to the sheet delivery roller 64 (which is of known type). During the feeding of the sheet any other sheets which may have been drawn along with it strike 115 against the rear side of the raising batten and do not reach the delivering roller. At the extreme front end of the pile table 27, immediately behind the rear side of the raising batten 61 a feeler nozzle 30 is arranged which is connected 120 on the one hand by means of a conduit 65 with the air control device (not shown) and on the other hand by means of the conduit 31 with the cylinder 33 in which the piston 32 is located.

The pile table 27 is located sufficiently low down 125 with regard to the delivering roller 64 to provide a certain distance between the sheet which is drawn off and the feeler nozzle. This is, however, insufficient, particularly with high speeds of rotation, to ensure that the sheet shall not contact 130 again with the feeler nozzle. It is only by means of the arrangement of the raising batten 61 that the sheet is moved so far away from the feeler nozzle 30 that it can no longer be sucked up by the latter (Fig. 3).

During the operation of lifting the sheet off, the suction is put into operation in the conduit of the lifting device 52, and is put out of operation in the suction conduit 65 of the feeler nozzle 30. In order to facilitate the separation of the sheets, 140 brushes 66 or the like are preferably fixed to the raising batten 61 in proximity to the lifting devices 52, the said brushes 66 or the like serving to wipe away any second sheet or sheets which may have been lifted together with the top one 145 by the lifting device. In addition to this in proximity to the brushes air blast members 67 are provided which loosen the pile in known manner by means of a blast of air at the places at which the lifting devices operate. In the construc- 150

tional example illustrated only one suction lifting member 52 operating at the corner of the sheet, one wiping brush 66 and one air blast member 67, which is arranged on the raising batten 61 (constructed in the form of a hollow member connected to the air blast control) are shown. The air blast nozzles can, however, also be arranged in other ways on the raising batten 61.

The device for delivering the individual sheets to the machine is constructed in the constructional example shown, in the form of a suction-operated delivering roller 64, which is driven from the shaft 2 by means of pinions 68, 69 (Fig. 2) and is moved laterally to-and-fro by means of a swinging lever 70 once in the course of a working operation, a hollow shaft 71 carrying the suction nozzles of the roller 64 being meanwhile guided in a longitudinal slot 73 provided in a guide member 74. The sheet which is brought on to the delivering roller 64 by the sheet lifting device 52 or the grippers (not shown in the drawings) of the latter is fed forwards and laterally by the delivering roller when the suction is in operation, so that the corner of the next sheet on the pile is immediately exposed and is ready for the lifting device 52 to operate upon it. In order to utilize to the full extent the extraordinary rapidity of feed of the sheets obtained in this way, it is essential to employ the arrangement of the raising batten according to the invention so as to avoid the occurrence of disturbances in the control of the sheet feeding operation.

It will, of course, be understood that the raising batten can also be advantageously employed with any other sheet feeding device having any desired sheet lifting and advancing device, and likewise in cases where instead of the suction feeler nozzle another device, for example, a gripper, is employed for controlling the feed, in order to avoid repeated operation of the control member by one and the same sheet whilst the latter is still being drawn off the pile.

I claim as my invention:

1. A paper feeding machine having in combination, a table, means for feeding a feathered bank of sheets to the table, pneumatic means cooperating with the front end of the bank for controlling the feed of the bank to maintain its front end in substantially uniform position, vertically movable mechanical means for lifting the foremost sheet, and means to actuate the vertically movable means in unison with the operation of the pneumatic means.

2. A sheet feeding device for feeding a fanned out pile of sheets to sheet separating devices, wherein for the purpose of compensating for the irregularities in feeding caused by the non-uniformity of the position of the sheets with regard to one another, the forward feed movement of the pile is controlled by the position of the front end of the pile itself by the employment of suction nozzles arranged beneath the pile and cooperating with a poppet piston and ratchet and pawl gear including a pawl arm oscillatably mounted to support a pawl operating upon the pile feeding means characterized in that the piston (32) cooperating with the suction control-nozzle (30) operates upon a member (37) elastically and yieldingly connected to the pawl arm and guiding the pawl (8) of the ratchet and pawl gear which effects the pile feeding movement in such manner that when the nozzle (30) is closed the pawl (8) is prevented by a guide track (42) on the said member (37) from engaging with the ratchet (12), and when the

nozzle is not closed the said pawl (8) is adapted to engage the said ratchet.

3. A sheet feeding device according to claim 1, characterized in that between the front end of the pile table (27) or the control device (30) respectively and the sheet feeding roller (64) a raising batten (61) actuated by a shaft (2) is arranged which lifts the sheet which is about to be drawn off to such an extent that it can no longer come under the action of the control device.

4. A sheet feeding device for feeding a fanned out pile of sheets to sheet separating devices, wherein for the purpose of compensating for the irregularities in feeding caused by the non-uniformity of the position of the sheets with regard to one another, the forward feed movement of the pile is controlled by the position of the front end of the pile itself by the employment of suction nozzles arranged beneath the pile and cooperating with a poppet piston and a ratchet and pawl gear operating upon the pile feeding means characterized in that the piston (32) cooperating with the suction control-nozzle (30) operates upon a member (37) elastically and yieldingly connected to the pawl arm and guiding the pawl (8) of the ratchet and pawl gear which effects the pile feeding movement, in such a manner that when the nozzle (30) is closed the pawl (8) is prevented by a guide track (42) on the said member (37) from engaging with the ratchet (12), and when the nozzle is not closed the said pawl (8) is adapted to engage the said ratchet.

5. A paper feeding machine having in combination, a table, means for feeding a feathered bank of sheets to the table, pneumatic means cooperating with the front end of the bank for controlling the feed of the bank to maintain its front end in substantially uniform position, and mechanical means for lifting the foremost sheet in unison with the operation of the pneumatic means, said mechanical means acting as a stop for the next sheet below.

6. A paper feeding machine having in combination, a table, means for feeding a feathered bank of sheets to the table, pneumatic means cooperating with the front end of the bank for controlling the feed of the bank to maintain its front end in substantially uniform position, mechanical means for lifting the foremost sheet in unison with the operation of the pneumatic means, said mechanical means acting as a stop for the next sheet below, and brushes carried by said mechanical means and engageable with the sheet next the foremost sheet to separate the two sheets.

7. A paper feeding machine having in combination, a table, a paper feeding roll arranged to feed a feathered bank of sheets to and along the table, a ratchet wheel geared to the roll to operate the same, a swinging pawl arm pivoted concentrically of the ratchet wheel, a pawl pivoted at one end to the arm and engaging the ratchet wheel at its other end, a roller on said pawl, a segment pivoted concentrically of the ratchet wheel and having a cam portion whereon said roller rests, said cam portion having a low part wherein the roller normally rests to permit engagement of the pawl and ratchet and having a high part for permitting oscillation of the pawl free from the ratchet, means for constantly oscillating the pawl arm, said segment normally oscillating with said pawl arm and with the roller on the low part, and pneumatic means controlled by the position of the foremost sheet for holding the segment against movement and releasing the segment for movement.

8. A paper feeding machine having in combination, a table, a paper feeding roll arranged to feed a feathered bank of sheets to and along the table, a ratchet wheel geared to the roll to operate the same, a swinging pawl arm pivoted concentrically of the ratchet wheel, a pawl pivoted at one end to the arm and engaging the ratchet wheel at its other end, a roller on said pawl, a segment pivoted concentrically of the ratchet wheel and having a cam portion whereon said roller rests, said cam portion having a low part wherein the roller normally rests to permit engagement of the pawl and ratchet and having a high part for permitting oscillation of the pawl free from the ratchet, means for constantly oscillating the pawl arm, said segment normally oscillating with said pawl arm and with the roller on the low part, a ratchet segment on said first segment, a pawl pivoted on a fixed axis to cooperate with the ratchet segment, and pneumatic means controlled by the position of the foremost sheet for operating said pawl. 80
9. A paper feeding machine having in combination, a table, a paper feeding roll arranged to feed a feathered bank of sheets to and along the table, a ratchet wheel geared to the roll to operate the same, a swinging pawl arm pivoted concentrically of the ratchet wheel, a pawl pivoted at one end to the arm and engaging the ratchet wheel at its other end, a roller on said pawl, a segment pivoted concentrically of the ratchet wheel and having a cam portion whereon said roller rests, said cam portion having a low part wherein the roller normally rests to permit engagement of the pawl and ratchet and having a high part for permitting oscillation of the pawl free from the ratchet, means for constantly oscillating the pawl arm, said segment normally oscillating with said pawl arm and with the roller on the low part, a ratchet segment on said first segment, a pawl pivoted on a fixed axis to cooperate with the ratchet segment, a pneumatic cylinder mounted adjacent said last pawl, a piston in said cylinder having a rod projecting from one end and engaging the 100 last pawl, a suction tube connected to the cylinder at the end adjacent the second pawl, a suction nozzle branching from said tube and opening through the table beneath the forward end of the foremost sheet, and mechanical means for lifting the foremost sheet to cause opening of the nozzle, said mechanical means acting as a stop for the next sheet below. 105
10. A paper feeding machine having in combination, a table, a paper feeding roll arranged to feed a feathered bank of sheets to and along the table, a ratchet wheel geared to the roll to operate the same, a swinging pawl arm pivoted concentrically of the ratchet wheel, a pawl pivoted at one end to the arm and engaging the ratchet wheel at its other end, a roller on said pawl, a segment pivoted concentrically of the ratchet wheel and having a cam portion whereon said roller rests, said cam portion having a low part wherein the roller normally rests to permit engagement of the pawl and ratchet and having a high part for permitting oscillation of the pawl free from the ratchet, means for constantly oscillating the pawl arm, said segment normally oscillating with said pawl arm and with the roller on the low part, a ratchet segment on said first segment, a pawl pivoted on a fixed axis to cooperate with the ratchet segment, a pneumatic cylinder mounted adjacent said last pawl, a piston in said cylinder having a rod projecting from one end and engaging the 115 last pawl, a suction tube connected to the cylinder at the end adjacent the second pawl, a suction nozzle branching from said tube and opening through the table beneath the forward end of the foremost sheet, and mechanical means for lifting the foremost sheet to cause opening of the nozzle, said mechanical means acting as a stop for the next sheet below. 120
11. A paper feeding machine having in combination, a table, a paper feeding roll arranged to feed a feathered bank of sheets to and along the table, a ratchet wheel geared to the roll to operate the same, a swinging pawl arm pivoted concentrically of the ratchet wheel, a pawl pivoted at one end to the arm and engaging the ratchet wheel at its other end, a roller on said pawl, a segment pivoted concentrically of the ratchet wheel and having a cam portion whereon said roller rests, said cam portion having a low part wherein the roller normally rests to permit engagement of the pawl and ratchet and having a high part for permitting oscillation of the pawl free from the ratchet, means for constantly oscillating the pawl arm, said segment normally oscillating with said pawl arm and with the roller on the low part, a ratchet segment on said first segment, a pawl pivoted on a fixed axis to cooperate with the ratchet segment, a pneumatic cylinder mounted adjacent said last pawl, a piston in said cylinder having a rod projecting from one end and engaging the 130 last pawl, a suction tube connected to the cylinder at the end adjacent the second pawl, a suction nozzle branching from said tube and opening through the table beneath the forward end of the foremost sheet, and mechanical means for lifting the foremost sheet to cause opening of the nozzle, said mechanical means acting as a stop for the next sheet below. 135
12. A paper feeding machine having in combination, a table, a paper feeding roll arranged to feed a feathered bank of sheets to and along the table, a ratchet wheel geared to the roll to operate the same, a swinging pawl arm pivoted concentrically of the ratchet wheel, a pawl pivoted at one end to the arm and engaging the ratchet wheel at its other end, a roller on said pawl, a segment pivoted concentrically of the ratchet wheel and having a cam portion whereon said roller rests, said cam portion having a low part wherein the roller normally rests to permit engagement of the pawl and ratchet and having a high part for permitting oscillation of the pawl free from the ratchet, means for constantly oscillating the pawl arm, said segment normally oscillating with said pawl arm and with the roller on the low part, a ratchet segment on said first segment, a pawl pivoted on a fixed axis to cooperate with the ratchet segment, a pneumatic cylinder mounted adjacent said last pawl, a piston in said cylinder having a rod projecting from one end and engaging the 140 last pawl, a suction tube connected to the cylinder at the end adjacent the second pawl, a suction nozzle branching from said tube and opening through the table beneath the forward end of the foremost sheet, and mechanical means for lifting the foremost sheet to cause opening of the nozzle, said mechanical means acting as a stop for the next sheet below, and brushes carried by said mechanical means and engageable with the sheet next the foremost sheet to separate the two sheets. 145

GEORG SPIESS.
